UNITED STATES PATENT OFFICE.

EDWIN W. SEEGER, OF SOUTH MILWAUKEE, WISCONSIN, ASSIGNOR TO THE CUTLER-HAMMER MFG. CO., OF MILWAUKEE, WISCONSIN, A CORPORATION OF WISCONSIN.

CONTROLLER FOR ELECTRIC ELEVATORS.

Application filed April 8, 1926, Serial No. 100,747. Renewed August 29, 1927.

This invention relates to controllers for electric elevators, and more particularly to automatic push button controllers for elevator systems of the three landing type.

5 An object of the invention is to provide improved and simplified control means of the above character.

Another and more specific object is to provide improved electrical interlocking means 10 for preventing interference when control push buttons are simultaneously operated within the car and on a landing, with the elevator car at the middle landing.

Another object is to provide a novel combination of electrical relays to insure proper 15 functioning of the various control elements.

Other objects and advantages of the invention will hereinafter appear.

The accompanying drawing illustrates an 20 embodiment of the invention which will now be described, it being understood that the embodiment illustrated is susceptible of modification without departing from the scope of the appended claims.

25 In the drawing, Figure 1 is a schematic and diagrammatic view of a controller embodying the invention; and

Fig. 2 is an across-the-line diagram of the controller illustrated in Fig. 1.

30 Referring to Fig. 1, A indicates the armature of a direct current motor to be supplied with current from lines L^{11} , L^{12} ; single-pole electromagnetic switches D^1 , D^2 and U^1 , U^2 being provided for establishing reverse 35 power connections for the motor, the switches D^1 and D^2 providing for operation of the motor in one direction and the switches U^1 and U^2 providing for reverse operation thereof. Switch D^1 is provided with 40 normally open auxiliary contacts 10, 11 and 12, whereas switch D^2 is provided with normally closed auxiliary contacts 13. Switch U^1 is likewise provided with normally closed auxiliary contacts 14, whereas switch U^2 is 45 provided with normally open auxiliary contacts 15, 16 and 17.

The motor may be of the compound-wound type, the series field thereof being indicated at SF. In series with the armature A are 50 a number of sections of accelerating resistance R^1 , R^2 , R^3 and R^4 , a relay AR being adapted when energized to effect gradual excision of said resistance sections and being also adapted to finally short-circuit the series 55 field SF. Relay AR is provided with nor-

mally closed auxiliary contacts 18, and movement of said relay in either direction for opening or closing said contacts is retarded by means of a double-dashing dashpot, as shown. The shunt field SHF of the motor 60 is adapted to be connected across the line in parallel with the shunt coil SHB of a suitable brake (not shown) upon closure of the normally open contacts 19, 20 and 21 of an electro-responsive switch FB, as herein-after more fully described. A field discharge resistance FDR may also be provided in parallel with the shunt field. 65

As aforeindicated the present invention is particularly adapted for automatic control of an elevator system of the three landing type, wherefore I have provided three landing door switches DS^1 , DS^2 and DS^3 , each of said switches being adapted to be closed or opened, depending upon closure or opening of its respective landing door (not shown), the arrangement being such that the elevator car cannot be operated for movement in either direction unless all of the landing doors are in closed position. 70

Arranged at suitable points in the elevator shaft or hatchway are a plurality of switches adapted to be operated by a cam C or other fixed portion of the car. The switch indicated at DOT is adapted to prevent overtravel of the car in a downward direction, through opening of its normally closed contacts 22. Switch DS is adapted to effect stopping of the motor and consequently of the car, when the latter in traveling downward is in proper position with respect to the bottom floor or landing, due to opening of the normally closed contacts 23 thereof. Switch MLD is arranged to effect stopping of the car at the middle landing, under certain conditions, when the car is moving downwardly from the top or upper landing, upon opening of its contacts 24, said contacts being biased by means of spring 25 to closed position but are held and locked 90 in open position under certain conditions, as hereinafter more fully described. Switch MLU is similarly arranged to effect stopping of the car at the middle landing, under certain conditions, when the car is moving upwardly from the bottom or lower landing upon opening of its contacts 26, said contacts being also biased to closed position by spring 27 but are held and locked in open 95 position, as shown, under certain conditions 100

105

110

hereinafter set forth. Switch US is adapted to effect stopping of the motor and consequently of the car, when the latter in traveling upward is in proper position with respect to the top floor or landing, due to opening of the normally closed contacts 28 thereof. Switch UOT is adapted to prevent overtravel of the car in an upward direction, through opening of its normally closed contacts 29.

Push button switches L^1 , L^2 and L^3 , located at the bottom, middle and top landings, respectively, are adapted when depressed to direct and control movement of the car to the corresponding floor or landing; switch L^1 being provided with normally open down contacts, whereas switches L^2 and L^3 are each provided with normally open down contacts and normally closed up contacts. Push button switches C^1 , C^2 and C^3 , located within the elevator car, are each provided with normally open down contacts and normally closed up contacts, said switches being likewise operable to direct and control movement of the car to the several landings. Also located within the car is a "Stop" push button,—the latter being operable to effect stopping of the car at any desired point in its travel. The car door switch CS is adapted to prevent movement of the car from any position thereof prior to closure of the car door.

A relay MLR is provided, which comprises normally open main contacts 30 and 31 and normally closed auxiliary contacts 32 and 33, the operating winding of said relay being adapted to be energized only upon depression of the landing push button L^2 or the car push button C^2 for calling or directing the car to the middle landing of the elevator shaft.

The operation of the controller will now be described with particular reference to the simplified diagram shown in Fig. 2. Assuming the elevator car to be at the bottom or lower landing, with the car door closed and each of the landing doors closed, and further assuming that it is desired to call the car to the top or upper landing,—the push button L^3 is depressed, thereby providing an energizing circuit for the operating windings of switches U^1 and U^2 . This circuit may be traced from line L^{11} through contacts 22 of switch DOT and contacts 29 of switch UOT, thence through auxiliary contacts 13 of switch D^2 and auxiliary contacts 14 of switch U^1 , thence through the respective up contacts of push button switches C^1 , C^2 and C^3 , thence through the down contacts of push button switch L^3 and through the windings of switches U^1 and U^2 in parallel, thence through contacts 28 of switch US and normally closed auxiliary contacts 33 of relay MLR, through the winding of switch FB, contacts CS of the car door switch and the

normally closed contacts of the "Stop" push button switch, thence through the contacts of landing door safety switches DS^1 , DS^2 , and DS^3 , and through normally closed contacts 18 of switch AR to line L^{12} . Switches U^1 and U^2 are thus closed to provide an energizing circuit for the motor, which circuit may be traced from line L^{11} through the contacts of switch U^2 , through the armature A and the contacts of switch U^1 , thence through series field SF and through resistance sections R^1 , R^2 , R^3 and R^4 in series to line L^{12} .

Upon closure of the normally open auxiliary contacts of switch U^2 , a maintaining circuit is provided for the windings of said switch and switch U^1 , which circuit extends from line L^{11} through contacts 22 and 29, as aforescribed, thence by conductor 34 through auxiliary contacts 15 and 17 of switch U^2 , thence by conductor 35 through the windings of switches U^1 and U^2 in parallel, and thence to line L^{12} in the manner previously traced; whereas switch U^1 in closing effects opening of its auxiliary contacts 14, thereby disconnecting all push button control stations from the line, except the "Stop" button, pending travel of the car through the range pre-selected which results in opening of contacts 28 of hatchway limit switch US to interrupt the circuits aforescribed, thus bringing the car to rest at the upper landing.

As indicated in the drawing the auxiliary contacts 14 of switch U^1 are so constructed and arranged that they will remain closed for an interval of time after closure of the auxiliary contacts of switch U^2 to provide for establishment of the maintaining circuit aforescribed; whereas the auxiliary contacts 13 of switch D^2 are similarly constructed and arranged so that they will remain closed for an interval of time after closure of the auxiliary contacts of switch D^1 , as hereinafter more fully described.

Also upon closure of the auxiliary contacts of switch U^2 an energizing circuit is provided for the operating winding of relay AR, said circuit extending from line L^{11} to contact 15, as heretofore traced, thence to contact 16, and by conductor 36 through the winding of said relay to line L^{12} . Closing movement of accelerating relay AR is retarded in the manner aforescribed, thus gradually bringing the motor up to speed, whereas the auxiliary contacts 18 of said relay are opened to include the resistance section x in circuit with the windings of switches U^1 , U^2 and FB to permit holding energization thereof, while preventing operating energization of said windings, or of the windings of switches D^1 and D^2 for a predetermined period after interruption of the first mentioned energizing circuit. This is due to the provision of the dash-pot on

relay AR which retards the reclosing movement of the auxiliary contacts 18.

The party who has called the car to the top landing is therefore given sufficient time 5 after arrival of the car to open the landing door, with consequent opening of switch DS³, prior to closure of said auxiliary contacts 18. After entering the car and closing the top landing door and the car door, the 10 occupant may dispatch the car to the middle or the bottom landing by operating the switch C² or C¹, respectively.

As will be apparent, if the car were dispatched to the top landing, by a party in the 15 car at the bottom landing through operation of the switch C³, the control system would function in a manner similar to that just described, a similar energizing circuit being thus completed which would extend from 20 line L¹¹ through the down contacts of push button switch C³, by conductor 37 through the windings of switches U¹ and U² in parallel, and thence to line L¹² as previously traced.

25 The aforementioned operation of the car push button switch C² (with the car at the top landing) would complete an energizing circuit for the winding of relay MLR, said circuit extending from line L¹¹ to and 30 through the up contacts of push button switch C¹, as heretofore traced, thence through the down contacts of switch C², by conductor 38 through the winding of relay MLR, thence by conductor 39 through contacts CS, and to line L¹² as previously traced.

Operating energization of the winding of relay MLR effects closure of the main contacts 30 and 31 thereof and simultaneous opening of the auxiliary contacts 32 and 33. 40 The cam operated switches MLD and MLU are provided with mechanical interlocking means whereby either of the contacts 24 and 26, respectively, may be opened while the other remains closed, or both of said contacts may be simultaneously opened; but if 45 one of said contacts is closed the other contact will be automatically locked in open position.

50 Thus with the car at the top landing contact 26 will be locked in open position as illustrated, whereas contact 24 will then be in closed position, so that upon closure of contact 31 in the manner aforescribed an energizing circuit will be provided for the 55 operating windings of switches D¹ and D², said circuit extending from line L¹¹ to conductor 38 as last traced, thence by conductor 42 through said contact 31, by conductors 43 and 44 through said windings D¹ and D² in parallel, through normally closed contact 23 of switch DS, by conductor 45 through closed contact 24, and thence by conductors 40 and 41 through winding FB to line L¹² as heretofore traced.

60 65 Switch D¹ in closing effects closure of its

normally open auxiliary contacts 10, 11 and 12 thereby providing a maintaining circuit for the windings of switches D¹, D² and FB, said maintaining circuit extending from line L¹¹ through contacts 22 and 29, by conductor 46 through auxiliary contacts 10 and 12, by conductor 47, and thence by conductor 44 through said windings to line L¹² as just traced. A maintaining circuit for the winding of relay MLR is likewise provided, said 70 maintaining circuit extending from line L¹¹ to conductor 47 as last traced, thence by conductor 43 through contact 31, by conductor 42 through said winding, and by conductor 39 through contacts CS to line L¹² as heretofore traced. Closure of said auxiliary contacts also provides an energizing circuit for the winding of relay AR, said circuit extending from line L¹¹ to auxiliary contact 10, thence through contact 11, by conductors 48 and 36 through said winding 75 to line L¹².

The motor is thus started and accelerated to effect movement of the car in a downward direction, whereas upon downward movement of the car to a position wherein the cam C effects opening of contact 24 the maintaining circuits of the windings of switches D¹, D² and FB and the maintaining circuit of the winding of relay MLR will be interrupted, and consequently the motor will be 80 stopped when the car is properly positioned at the middle landing.

85 As aforeindicated the normally closed auxiliary contacts 13 of switch D² remain closed for a sufficient period after completion of the energizing circuit of the latter to permit completion of the aforescribed maintaining circuits through closure of the normally open auxiliary contacts of 90 switch D¹.

95 With the car at the middle landing the same may be dispatched or called to the top landing by momentarily depressing the car push button switch C³ or top landing push button switch L³, respectively; or the car may be dispatched or called to the bottom landing by momentarily depressing the car push button switch C¹ or bottom landing push button switch L¹.

100 Thus, assuming depression of push button switch C¹ an energizing circuit is provided for the windings of switches D¹ and D², said circuit extending from line L¹¹ through normally closed contacts 22, 29, 13 and 14 and through the normally open down contacts of switch C¹, by conductors 49, 50 and 44 through said windings, thence through the normally closed contacts 23 of switch DS and the auxiliary contacts 10 and 12 of switch D¹, and an energizing circuit will be provided for the winding of relay AR, in the manner heretofore described.

- 5 The motor will thus be operated to effect movement of the car in a downward direction, whereas upon engagement of the cam C with the operating element of switch DS the normally closed contacts 23 of the latter 10 will be opened, thereby interrupting the energizing circuit of the windings D¹ and D² to bring the car to rest at the bottom landing.

It will be noted that upon movement of the car from the top or middle landing to the 15 bottom landing the cam C on the car acts to permit closure of contacts 26 of switch MLU, thus locking contacts 24 of switch MLD in open position. Similarly upon movement of the car from the bottom or 20 middle landing to the top landing cam C acts to permit closure of contacts 24 of switch MLD, thus locking contacts 26 of switch MLU in open position. In this manner positive 25 control of the desired direction of travel of the car from any position thereof is insured. Moreover, by the arrangement aforescribed non-interference between the car push button control stations and the landing push button control stations is insured.

What I claim and desire to secure by Letters Patent is:

1. In a control system for electric elevators of the three landing type, the combination with means for effecting movement of the car from one landing to the other landings selectively, said means comprising a plurality of independently operable push button switches, means adapted upon temporary closure of one of said push button switches to effect operating energization of electroresponsive switches for effecting movement of the car in a predetermined direction, means adapted upon operation of said electroresponsive switches respectively to provide a maintaining circuit for the latter independently of said push button switches, and associated means also adapted upon operation of said electroresponsive switches to simultaneously disconnect all of said push button switches from the line pending movement of the car to the position preselected by closure of said first-mentioned push button switch.

2. In a controller for electric elevators of the three landing type, the combination with a plurality of push button switches for directing movement of the car to the respective landings, means controlled by certain of said switches for effecting movement of the car to the middle landing, said means comprising a relay having a winding adapted to be energized only upon closure of one of said last mentioned switches, a plurality of sets of contacts controlled by said relay, electroresponsive switches the windings of which

are respectively adapted to be connected in circuit with one of said sets of contacts, means dependent upon the position of the car with respect to the middle landing for effecting completion of a circuit for the 70 windings of said electroresponsive switches selectively, said means comprising a plurality of switches independently biased to closed position, independent operating means for said switches located in the path of the car, and interlocking means for insuring against simultaneous closure of said switches.

3. In a controller for electric elevators of the three landing type, the combination with a car and an electric motor for driving the same, electroresponsive switches adapted when energized to complete circuit for the motor for effecting operation thereof in opposite directions selectively, push button control switches for initially completing the energizing circuits of said electroresponsive switches, auxiliary contacts on the latter adapted to provide maintaining circuits therefor, hatchway limit switches in the path of the car for interrupting said maintaining circuits when the car reaches the top or bottom landing respectively, a plurality of independently operable switches in the path of the car at the middle landing of the elevator, means for rendering said last mentioned switches effective for stopping the car at the middle landing, said means comprising a relay having a winding adapted to be energized upon closure of certain of said push button switches, contacts controlled by said relay, said contacts being respectively adapted to provide maintaining circuits for the winding of said relay and for said electroresponsive switches selectively, and means for rendering said maintaining circuits subject to control by said middle landing switches to thereby insure interruption of said circuits upon positioning of the car at the middle landing.

4. In a control system for electric elevators of the three landing type, the combination with means for effecting movement of the car toward the middle landing, of means operable under given conditions to effect automatic stopping of the car at the middle landing, said means comprising a plurality of switches independently biased to closed position, one of said switches being operable directly by the car when the latter is moving upwardly and the other of said switches being operable directly by the car when the latter is moving downwardly, and mechanical interlocking means for insuring open positioning of either of said switches when the other is in closed position.

5. In a control system for electric elevators of the three landing type, the combination with means for effecting movement of the car toward the middle landing, of means operable under given conditions to

- effect automatic stopping of the car at the middle landing, said means comprising a plurality of switches independently biased to closed position, one of said switches being 5 operable directly by the car when the latter is moving upwardly and the other of said switches being operable directly by the car when the latter is moving downwardly, and mechanical interlocking means for insuring 10 open positioning of either of said switches when the other is in closed position, said last-mentioned means being also adapted to permit simultaneous opening of both of said switches.
- 15 6. In a control system for electric elevators of the three landing type, the combination with push button control means for effecting movement of the car in either direction toward the middle landing, of means 20 dependent upon the direction of travel of the car to effect automatic stopping thereof at the middle landing, said means comprising a pair of switches independently biased to closed position and mechanical interlocking 25 means for insuring open positioning of either of said switches when the other is in closed position, said last-mentioned means being also adapted to permit simultaneous open 30 positioning of both of said switches, integral operating means for the respective switches located in the path of the car and adapted to permit closure of the switch first disengaged by the car when the latter is moving in one direction and to insure opening of 35 said switch during movement of the car in the reverse direction, and additional push button control means for effecting movement of the car in reverse directions past
- the middle landing while positively neutralizing the aforementioned stopping means. 40
7. In a controller for electric elevators of the three landing type, the combination with a car and a driving motor therefor, electro-responsive reversing switches for said motor, push button switches at the respective landings and corresponding push button switches within the car for selectively controlling the initial energizing circuits of said reversing switches, auxiliary contacts on the latter for maintaining the energizing circuits thereof 45 independently of said push button switches, limit switches in the hatchway adjacent to the top and bottom landings for interrupting said energizing circuits respectively, a plurality of independently operable limit 50 switches in the hatchway adjacent to the middle landing, means for rendering said last-mentioned limit switches effective for stopping the car at the middle landing, said means comprising a relay having an operating winding to be energized only upon closure of one of the push button switches corresponding to the middle landing, contacts controlled by said relay for rendering the 55 energizing circuits of said reversing switches subject to control by said last-mentioned limit switches, means for insuring against closure of one of said last-mentioned limit switches when the car is above the middle landing, and means for insuring against closure of another of the same when the car is 60 below the middle landing. 70

In witness whereof, I have hereunto subscribed my name.

EDWIN W. SEEGER.
